Primary Examiner — Susan E. Krakower*Assistant Examiner* — Lisa A Grabenstetter(74) Attorney, Agent, or Firm — Troutman Sanders LLP; Ryan A. Schneider(57) CLAIM

The ornamental design for a trumpet, as shown and described.

DESCRIPTION

FIG. 1 is a front view of a trumpet showing my new design.

FIG. 2 is a back view thereof;

FIG. 3 is a top plan view thereof;

FIG. 4 is a bottom plan view thereof;

FIG. 5 is a left side view thereof;

FIG. 6 is a right side view thereof; and,

FIG. 7 is a front left perspective view thereof.

The broken line portions of FIGS. 5 and 6 are included to show unclaimed subject matter only and form no part of the claimed design.
